UNITED STATES PATENT OFFICE.

LESTER R. WELLMAN, OF CHICAGO, ILLINOIS, ASSIGNOR TO FRIEDLEY-VOSHARDT COMPANY, OF CHICAGO, ILLINOIS, A CORPORATION OF ILLINOIS.

DESIGN FOR A HUSK FOR LIGHTING FIXTURES.

Application filed September 12, 1928. Serial No. 28,115. Term of patent 3½ years.

To all whom it may concern:

Be it known that I, LESTER R. WELLMAN, a citizen of the United States residing at Chicago, in the county of Cook and State of Illinois, have invented a new, original, and ornamental Design for a Husk for Lighting Fixtures, of which the following is a specification, reference being had to the accompanying drawing, forming part thereof.

Fig. 1 is a top view;

Fig. 2 is a side elevation showing my new design.

I claim:

The ornamental design for a husk for lighting fixtures, as shown.

LESTER R. WELLMAN.
